UNITED STATES PATENT OFFICE.

LEON F. PARKHURST, OF PITTSFIELD, MASSACHUSETTS, ASSIGNOR TO GENERAL ELECTRIC COMPANY, A CORPORATION OF NEW YORK.

ELECTRIC HEATER.

1,028,383.

Specification of Letters Patent.

Patented June 4, 1912.

Application filed April 26, 1909. Serial No. 492,410.

To all whom it may concern:

Be it known that I, LEON F. PARKHURST, a citizen of the United States, residing at Pittsfield, in the county of Berkshire and 5 State of Massachusetts, have invented certain new and useful Improvements in Electric Heaters, of which the following is a specification.

This invention relates to electric heaters 10 and has for its object the provision of means whereby the heating unit is resiliently or yieldingly held in contact with the body to be heated, so as to overcome the detrimental effect upon the thermal relation between the 15 unit and the body to be heated, due to expansion.

In carrying out my invention, I provide in 20 connection with the body to be heated and a heating unit, which may be of the flat type, resilient clamping means for securing the unit to the body. A spring clamp or fastener is provided, which, while holding the parts in thermal relation, provides for a yielding contact to enable the parts to 25 expand.

In the accompanying drawings, in which I have shown my invention embodied in two different forms for purposes of illustration, Figure 1 represents a view partly in section, of a fluid receptacle having my invention applied thereto; Fig. 2 represents a disassembled view of the parts; Fig. 3 represents a plan view of the base equipped with my spring clamping arrangement; Fig. 4 represents an elevation of another form of my invention; Fig. 5 represents a sectional enlarged view of the same; and Fig. 6 a fragmentary plan view.

Referring to the drawings, 10 represents 40 a fluid receptacle which may be of any desired shape and material, such, for instance, as the shape shown in Fig. 1, made of aluminum. The bottom of this receptacle has secured to it a cup-shaped member 11, having 45 screw-threaded corrugations 12. This member 11 may be in the nature of a reinforcing plate and secured to the bottom by brazing or similar method as described in the manner disclosed in the patent to E. F. 50 Shailer and O. D. Storer, No. 1,006,692. This cup-shaped member 11 is adapted to receive a heating unit 13 which is secured in yielding contact with the bottom of the receptacle by means of the base 14, which

forms a clamping device. This base consists of a cup-shaped member similar to member 11 screw-threaded to engage the threads 12 and adapted to screw over the member 11. The bottom of this member, which engages the heating unit, is provided with spring lugs 15, which are struck up from the base by expanding the metal, as shown. I have shown three of these lugs to engage the bottom, although it is evident that any number may be provided and it is 65 also evident that they may be constructed in any desired manner. When the base is secured on to the member 11, the lugs press the heating unit into engagement with the bottom of the receptacle with a yielding 70 pressure, so that the unit will be in good thermal relation with the bottom of the receptacle, regardless of any expansion which may occur.

Figs. 4, 5, and 6 show my invention in a 75 slightly modified form. In this case, as above, the reinforcing plate 16 is secured to the bottom of the receptacle, but the spring member in this case is a separate piece secured to the bottom of the heating 80 unit and may therefore be of selected material to retain its elasticity under repeated heating. This member 17 has substantially the same length as the diameter of the heating unit and is pivoted at its middle 85 portion to the center of the heating unit. This strip is a spring metal and is concaved away from the unit, as shown. Lugs 18 are riveted to the flange of the member 16 at opposite sides thereof, so as to engage 90 the spring strip 17. This unit is clamped in place by forcing the member into the lugs 18, so as to place the spring 17 under tension and may be removed by turning the member on its pivot and releasing it from 95 the lugs.

While I have shown my invention as embodied in concrete structure for purposes of illustration, it should be understood that I do not limit my invention thereto, since various modifications will suggest themselves to those skilled in the art without departing from the spirit of my invention, the scope of which is set forth in the annexed claims.

What I claim as new and desire to secure by Letters Patent of the United States, is,

1. An electric heater comprising a body

to be heated, a flat heating unit located beneath the said body and resilient means for securing the unit to the body.

2. An electric heater comprising a body 5 to be heated, a flat heating unit located beneath the said body and a spring clamp for securing the unit to the body.

3. An electric heater comprising a fluid receptacle, an auxiliary member rigidly 10 secured to the bottom of said receptacle to reinforce the same, a flat heating unit and means including a resilient device for securing the unit to said member.

4. An electric heater comprising a fluid 15 receptacle, a flat heating unit and yielding clamping means for securing the unit to the bottom of said receptacle.

5. An electric heater comprising a fluid 20 receptacle having a reinforced bottom, a flat heating unit and a resilient device for securing the heating unit to said bottom.

6. An electric heater comprising a body to be heated, a heating unit located beneath the said body and resilient means for yieldingly securing the effective heating surface 25 of the unit to the body.

7. An electric heater comprising a fluid receptacle, a heating unit and means for yieldingly securing the effective heating surface of the unit to the bottom of said receptacle. 30

8. An electric heater comprising a fluid receptacle having a reinforced bottom, a heating unit, and resilient clamping means for yieldingly securing the effective heating 35 surface of the unit to said bottom.

In witness whereof, I have hereunto set my hand this thirty-first day of March, 1909.

LEON F. PARKHURST.
